UNITED STATES PATENT OFFICE.

JASPER N. McCAY, OF WATTS, CALIFORNIA.

TRUSS-PAD.

1,377,260.

Specification of Letters Patent. Patented May 10, 1921.

Application filed September 17, 1920. Serial No. 410,874.

To all whom it may concern:

Be it known that I, JASPER N. McCAY, a citizen of the United States, residing at Watts, in the county of Los Angeles and

5 State of California, have invented certain new and useful Improvements in Truss-Pads, of which the following is a specification.

This invention relates to trusses and has 10 for its object the provision of means whereby the truss and the pad will conform to the movements of the wearer without getting out of place and without any discomfort to the wearer. The invention also seeks to provide 15 a truss which will more effectually support the rupture than trusses heretofore produced and without applying such excessive pressure to the parts as to impede the circulation of the blood. The invention is illus- 20 trated in the accompanying drawings and will be hereinafter fully set forth.

In the drawings—

Figure 1 is a perspective view of a truss embodying my invention;

25 Fig. 2 is an elevation of the pad indicating the position of the same when in use;

Fig. 3 is a detail transverse section on the line 3—3 of Fig. 1.

The belt 1 may be of leather or canvas or 30 any other material now generally employed for that purpose and will preferably house a spring plate 2 whereby it may be bent to fit the body of the wearer and will retain the curvature imparted thereto. On the inner

35 side of the belt over the shape-retaining spring 2, I provide a lining 3 which consists of a strip of sponge rubber, preferably of the same width as the belt and of sufficient length to bear against the portion of the

40 body encircled by the belt so that no part of the belt will come into contact with the flesh and irritate the same. The lining should be of sufficient thickness to effectually cushion the strap upon the body and as it is

45 very soft and pliable it will permit the belt to be drawn closely to the body so that it will not readily slip out of place and owing to the open cellular form of the material it will prove very cool and comfortable.

50 To one end of the strap or belt is secured a pad-carrying arm 4 of the usual construction and the base plate 5 of the pad is adjustably mounted upon this arm as will be readily understood. Upon the base plate 5, I secure

55 a pad 6 of sponge rubber having a head or body-engaging portion 7 which is shaped

to provide a convex inner surface of sufficient extent to bear against the body of the wearer in a comfortable manner and firmly support the ruptured part. The pad includes a neck or shank portion 8 which is secured directly to the base plate 5 and carries the head 7, as shown, and the upper portion of the shank or neck is shorter than the lower portion so that the head 7 will be 65 disposed in an inclined position and thereby conform more readily to the shape of the wearer's body than would otherwise be the case. The inclined position of the pad head, furthermore, causes it to exert a pressure upwardly as well as inwardly so that the ruptured part will be more effectually supported than with the pads now most commonly used. As the material of which the pad is formed is very yielding and of an open cellular 70 formation, it will be very cool and comfortable and will respond quickly to the movements of the body without causing any discomfort and without being dislodged. The described form and arrangement of the 75 pad will permit the upper part of the pad to follow the movements of the wearer's body while retaining the lower part in its operative position so that the rupture will be effectually supported and relieved of all 80 strain. The material employed also causes the pad and the belt lining to adhere to the body, while at the same time exerting a sufficient pressure to relieve the rupture of 85 strain and prevent spreading thereof so that 90 the blood may circulate freely and the health of the user is promoted.

Having thus described the invention, what is claimed as new is:

1. A truss comprising a belt, a lining of 95 sponge rubber on the belt, an arm secured to one end of the belt, and a pad secured to and adjustable along said arm, the pad comprising an integral head and shank of sponge rubber, the shank being of less diameter than 100 the head and the head being inclined relative to the shank.

2. A truss pad consisting of sponge rubber forming a head and a shank integral with and of less diameter than the head, the 105 shank extending outwardly from the head and the upper portion of the shank being shorter than the lower portion thereof whereby the head will be disposed in an inclined position.

In testimony whereof I affix my signature.

JASPER N. McCAY, [L. S.]
